UNITED STATES PATENT OFFICE.

CHARLES W. COOPER, OF PITTSBURGH, PENNSYLVANIA.

RAILWAY DRAFT APPLIANCE.

1,290,099.

Specification of Letters Patent.

Patented Jan. 7, 1919.

Application filed June 26, 1918. Serial No. 241,969.

To all whom it may concern:

Be it known that I, CHARLES W. COOPER, a citizen of the United States, residing at Pittsburgh, in the county of Allegheny and State of Pennsylvania, have invented certain new and useful Improvements in Railway Draft Appliances, of which the following is a specification, reference being had to the accompanying drawings.

- 10 This invention relates to certain improvements in railway draft appliances and has relation more particularly to a coupling of the Janney type and it is an object of the invention to provide a coupling having novel and improved means whereby the same is automatically locked together with means whereby the coupling may be conveniently released with the possibility of injury to the trainman substantially entirely eliminated.
- 15 20 It is also an object of the invention to provide an appliance of this general character having novel and improved means whereby the knuckle may be readily opened. Another object of the invention is to provide an appliance of this general character having novel and improved means whereby the coupling may be released by a trainman on the top of a car or on the ground and wherein the necessity of the trainman going
- 25 30 between cars is unnecessary.

The invention consists in the details of construction and in the combination and arrangement of the several parts of my improved railway draft appliance whereby certain important advantages are attained and the device rendered simpler, less expensive and otherwise more convenient and advantageous for use, as will be hereinafter more fully set forth.

40 The novel features of my invention will hereinafter be definitely claimed.

In order that my invention may be better understood, I will now proceed to describe the same with reference to the accompanying drawings, wherein:

Figure 1 is a fragmentary view partly in side elevation and partly in section illustrating a railway draft appliance constructed in accordance with an embodiment of my

45 50 invention.

Fig. 2 is a view in front elevation of my improved appliance as herein embodied.

Fig. 3 is a fragmentary view partly in horizontal section and partly in top plan

of my improved appliance as herein disclosed.

Fig. 4 is a fragmentary sectional view illustrating a connection between the swing block and cross bar as herein embodied, and

Fig. 5 is a fragmentary view partly in side elevation and partly in section illustrating a railway draft appliance constructed in accordance with a further embodiment of my invention.

As disclosed in Figs. 1 to 4 B denotes a car body including a front sill S and a draw head D. Operatively engaged with the body B is a draw head D of a car coupling of a well known Janney type and coacting with the head D in a well known manner is a knuckle K including a tail piece x provided in its free end portion with a notch or recess 1 to receive a vertically sliding latch or pin L.

As herein disclosed the latch or pin L enters within the draw head D through a suitable opening or slot 2 in the top thereof and the upper end portion of the latch or pin L is provided with a head 3. The head 3 has an upstanding ear 4 extending within a recess 5 formed in the under surface of a block 6 and the ear 4 is pivotally engaged with the block 6 through the medium of the pin 7 extending transversely of the block 6 and through the ear 4.

The rear portion of the block 6 in the under face thereof is provided with a second recess 8 in which extends an ear 9 carried by the member 10 and which member 10 is suitably anchored to the rear portion of the draw head D. Disposed transversely of the rear portion of the block 6 is a pin 7 which is also directed through the ear 9 whereby the block 6 is mounted for swinging movement in a vertical plane.

The rear face of the block 6 is provided with an outstanding finger or arm 11 extending within the opening 12 in an end portion of the cross bar 14. The cross bar 14 is carried by and extends laterally from a vertically movable bar 15 slidably supported by the sill S and an outstanding platform 16 arranged adjacent the top of the body B. The portion of the finger or arm 11 within the opening 12 is provided with a longitudinally directed and vertically disposed slot 17 through which is directed a pin 18

carried by the adjacent end portion of the arm 14. By this arrangement it will be perceived that upon downward movement being imparted to the bar, the outer end of the block 6 will be elevated and the latch or pin L raised to a position to release the same from the tail a of the knuckle K. The latch or pin L is adapted to drop by gravity and in order to facilitate this action the outer end portion of the block 6 is provided with a weight 19 herein disclosed as a plate and which weight 19 overbalances the weight of the bar 15 and the cross bar 14 carried thereby. The upper end portion of the bar 15 is provided with the hand grasp 20 so that a trainman may readily impart downward endwise movement thereto when said trainman is upon the top or platform 16 of the car.

20 Pivottally engaged at substantially midway its length with the end of the body B and in close proximity to the sill S is a lever 21. The inner end portion of the lever is bifurcated and straddles the bar 15 and is pivottally engaged therewith through the medium of the substantially horizontally disposed pin 22. The opposite end portion of the lever 21 extends to a side of the body B and is provided with the handhold 23 whereby the lever 21 may be conveniently locked by a trainman when on the ground. It will be self-evident that upon swinging the outer end of the lever 21 upwardly the bar 15 will be moved downwardly and thereby resulting in the desired raising of the latch or pin L.

A side wall of the draw head D is provided with an opening 24 through which extends a laterally directed arm 25 carried by the tail portion a of the knuckle K. In pivotal engagement with the outer end portion of the arm 25 is the foot portion b of a substantially L-shaped link 26. The stem c of the link 26 is pivottally engaged with the inner end portion of the cross head 27 carried by the lower end portion of the vertically disposed rod 28 supported for rotary movement by the sill S and the platform 16. The outer end portion of the head 27 is provided with the hand grasp 29 to afford means for manually operating the rod 28 so that upon rotation of the rod 28 in one direction the arms 25 will be moved inwardly of the draw head D and the knuckle K opened.

55 The cross head 27 is operated by a trainman upon the ground. Should the trainman be on the top of the car on the body B or on the platform 16, it is only necessary that the desired rotation be imparted to the rod 28 and preferably through the medium of the hand wheel 30 fixed to the upper end portion thereof.

In the embodiment of my invention as particularly disclosed in Fig. 5 the latch or

pin L' enters within the draw head D' from below and the lower end portion of the latch or pin L' is pivottally engaged with the block 6' which is also supported for swinging movement by the member 10'. The inner or rear end portion of the block 6' is also pivottally engaged with a cross bar 14' carried by the lower end portion of a bar 15' supported for endwise movement by the sill S' and the platform 16'. It will be understood that by imparting upward movement to the bar 15' the latch or pin L' will be caused to move downwardly to be disengaged from the tail a' of the knuckle K'. Co-acting with the bar 15' is a lever 21' for the same purpose as has been set forth relative to the lever 21.

The mechanism for opening the knuckle in this second embodiment of my invention is the same as has been fully set forth in connection with the embodiment of my invention as illustrated in Figs. 1 to 4.

From the foregoing description, it is thought to be obvious that a railway draft appliance constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a draw head and a knuckle of a car coupling, a sliding latch engageable with the knuckle for holding the knuckle against movement, a member extending from the draw head, a block pivottally engaged at one end with the outer end portion of the latch, and pivottally engaged adjacent its opposite end with the member, the second end portion of the block being provided with an outwardly directed finger, a bar supported for endwise movement, a cross bar extending laterally from said first named bar and provided with an opening in an end portion, the finger of the block extending within said opening and pivottally engaged to the cross bar.

2. In combination with a draw head and a knuckle of a car coupling, a sliding latch engageable with the knuckle for holding the knuckle against movement, a member extending from the draw head, a block pivottally engaged at one end with the outer end portion of the latch, and pivottally engaged adjacent its opposite end with the member, the second end portion of the block being provided with an outwardly directed finger

a bar supported for endwise movement, a cross bar extending laterally from said first named bar and provided with an opening in the end portion, the portion of the finger 5 within the opening in the cross bar being provided with a longitudinally disposed slot, and a pin carried by the cross bar and intersecting the opening thereof, said pin

being also directed through the slot in the finger.

In testimony whereof I hereunto affix my signature in the presence of two witnesses.

CHARLES W. COOPER.
